UNITED STATES PATENT OFFICE

CHARLES W. KIRSCH, OF STURGIS, MICHIGAN, ASSIGNOR TO KIRSCH COMPANY, OF STURGIS, MICHIGAN, A CORPORATION OF MICHIGAN

DRAPEY FIXTURE

Application filed April 30, 1930. Serial No. 448,618.

This invention relates to improvements in drapery fixtures and more particularly to supporting brackets and devices to be supported thereby for interchange with each other as, for example, a cornice element and curtainpole, the invention residing in part in the details of construction of the bracket and in certain fixtures mounted thereon and on the devices to be supported by said brackets.

10 The main object of the invention is to provide simple, cheap and efficient drapery fixtures possessing the various advantages hereinafter pointed out.

The invention is fully illustrated in the accompanying drawings, wherein:

Fig. 1 is a fragmentary top plan view of a supporting bracket and cornice member engaged therewith constructed and equipped with interengaging means in accordance with 20 the invention.

Fig. 2 is a side elevation of the bracket showing the face thereof opposed to the companion bracket of a pair.

Fig. 3 is a sectional view on the line 3—3 of Fig. 2.

Fig. 4 is a fragmentary perspective view of one end portion of the cornice member supported by said brackets.

Fig. 5 is a detail perspective of a plate of 30 the structure of Figs. 1 to 3, inclusive.

Fig. 6 is a plan view similar to Fig. 1, showing a curtain pole substituted for the cornice member.

Fig. 7 is a sectional view of the same on 35 the line 7—7 of Fig. 6.

Fig. 8 is a sectional view on the line 8—8 of Fig. 7.

Fig. 9 is a fragmentary perspective view 40 showing an end portion of a curtain pole equipped with a fixture constructed in accordance with the invention.

The brackets 1 of a pair thereof are each provided in the face opposing the other thereof, with a shallow horizontal groove 2 and a deeper vertical groove 3. The groove 2 extends from the rear edge of the bracket 1 to a point adjacent its front edge, the latter carrying an ornament 4 of suitable design 45 suitably secured thereto. The groove 3 extends from the upper edge of said bracket

to a point slightly below the lower wall of the groove 2.

A flat plate 5 of a thickness substantially equal to the depth of the groove 2 and having an upwardly extending bifurcated projection 6, is mounted in the groove 2, the projection 6 being disposed between the walls of the groove 3 and spaced from the inner wall of the latter.

The said bifurcated projection 6 of said 60 plate 5 cooperates with the groove 3 to receive and engage cooperative fixtures mounted upon the ends of cornice members 7 and curtain poles 8 to the end that either of these types of devices may be engaged with any 65 pair of said brackets for support thereby while also being held against rotation.

Thus, the cornice member 7 is provided at its ends with L-shaped plates 9, the main or body portion of each of which is provided 70 with a plurality of longitudinal slots 10 for the reception of fastening screws 10^a, said body portion lying in contact with the rear face of the member 9 and being adjustable relatively thereto as will be obvious. Said 75 body portion of the plate 9 is provided in its lower edge at a point adjacent to but spaced from its flange 11, with a slot 12 to receive the projection 6 of the plate 5 of the bracket. The flange 11 is of a width to be 80 snugly received in the groove 3 of the bracket, the lower end portion thereof lying within the free space behind the plate 5 when the projection 6 thereof engages in the slot 12.

Thus the plate 5 and its projection 6 co- 85 operate with the groove 3 to prevent the cornice member from moving longitudinally or downwardly from its intended position, while the flange 11 coacts with said groove 90 3 to prevent tilting of said cornice from its intended position.

The curtain pole 8 is equipped at each end thereof with a circular plate 14 having a short L-shaped flange 15 diametrically opposed to a twisted perforated projection 16. Said pole is provided with center projections or studs 17 having heads 18 spaced from the plates 14. The latter are provided with key-hole slots through which said heads 18 are 100

passed and in the narrower centrally disposed portions of which the shanks of said studs are received as said plates 14 are brought into concentric position with respect to the pole 8 to which they are secured by means of suitable fastening devices 19.

The said heads 18 of the studs 17 are received behind the projections 6 of the plate 5 as the shanks of said studs are received in the slot or recess 20 of said projection 6.

- 10 10 The short projections 21 of the L-shaped flange 15 are of such width as to fit snugly in the groove 3 in which they are engaged to hold the pole 8 against rotation relatively to the bracket, the cooperation of the plate 5 and groove 3 of the bracket with the fixture of the pole end being identical with that of said elements with respect to the cornice fixture.

- 15 20 The projection 16 is provided for permitting attachment of the outer edges of draperies thereto and thus performs a function wholly separate from the retaining and supporting means above described.

- 25 25 It is very desirable that curtain poles shall not be rotatable in order that only the uppermost parts of the surfaces thereof may be worn by the drapery suspension rings or, in the case of poles equipped with metallic 30 30 traverse rails for the suspension fixtures, that said rails be maintained in a fixed position relatively to the supporting brackets.

I claim as my invention:

- 35 1. A drapery fixture including a pair of parallel supporting brackets and a device spanning the space between said brackets, of grooves in the opposed faces of said brackets, plates secured thereto and spanning said grooves, there being free spaces between the inner faces of said plates and the inner opposed walls of said grooves, and end fixtures on said device, each including a member engaged in said space and with said plate and a part engaged with the side 45 walls of said grooves of said bracket.

- 40 2. A drapery fixture comprising a pair of brackets provided in their opposed faces with vertical grooves extending downwardly from their upper edges, plates spanning said 45 50 grooves and secured to said brackets, a member supported by said brackets and provided at its ends with a device provided with a formation to receive and engage one of said plates and a device to engage the side walls 55 of said groove for preventing rotation of said member.

In testimony whereof, I have hereunto set my hand this 19th day of April, 1930.

CHARLES W. KIRSCH.
